UNITED STATES PATENT OFFICE.

JULIAN S. GRAVELY, OF WYTHEVILLE, VIRGINIA, ASSIGNOR TO WINCHESTER REPEATING ARMS CO., OF NEW HAVEN, CONNECTICUT, A CORPORATION.

EXTENSION ROLLER-SKATE.

Application filed April 29, 1925. Serial No. 26,596.

My invention relates to an improvement in that class of roller-skates known as "extension" roller-skates on account of their adaptation to be extended to fit shoes of varying length, the object being to provide, at a low cost for manufacture, a simple, convenient and durable skate of the character described, constructed with particular reference to fewness of parts and rigidity in use.

With these ends in view, my invention consists in an extension roller-skate characterized by having its heel- and toe-plates provided with self-stiffening, rigidly-attached, telescopic girder-extensions, sliding one within the other, with means for clamping them rigidly together.

My invention further consists in an extension roller-skate characterized as described and having further details of construction and combinations of parts as will be hereinafter described and pointed out in the claim.

In the drawings:

25 Fig. 1 is a plan view of an extension roller-skate constructed in accordance with my invention.

Fig. 2 is a view thereof in side elevation.

Fig. 3 is a transverse, sectional view on the line 3—3 of Fig. 1.

Fig. 4 is a corresponding view on the line 4—4 of Fig. 1.

Fig. 5 is a corresponding view on the line 5—5 of Fig. 1.

35 Fig. 6 is a detached, perspective view of the front girder-extension.

Fig. 7 is a corresponding view of the rear girder-extension.

In carrying out my invention, as herein shown, I employ a self-stiffening heel-plate girder-extension 10 and a complementary, self-stiffening toe-plate girder-extension 11, these girder-extensions being struck up from heavy sheet-metal stock into trough-shaped form, by which they are rendered self stiffening. The upstanding, parallel, longitudinal flanges 12 of the heel-plate girder-extension 10 are formed upon their upper edges with rivet-lugs 13 entering rivet-holes 14 in the

heel-plate 15, in which they are swaged, 50 whereby the said extension 10 is rigidly attached to the heel-plate of the skate. The toe-plate girder-extension 11 is formed with corresponding stiffening flanges 16 and made just enough wider than the complementary extension 10 to permit the same to fit snugly within it, with opportunity for longitudinal but no lateral play. At its forward end, the extension 11 is formed with rivet-holes 17 for the reception of rivets 18, 60 by means of which the extension is rigidly secured to the toe-plate 19. At its forward end, the heel-plate girder-extension 10 is formed with a bolt-hole 20 for the reception of a clamping-bolt 21, also passing through 65 a long slot 22 in the extension 11, the said slot being long enough to provide for the maximum extension of the skate.

The self-stiffening extensions 10 and 11, as thus constructed, and organized with the 70 heel- and toe-plates 15 and 19, provide for uniting the said plates with the maximum of rigidity, lightness, range of extension, and ease of adjustment.

Otherwise than as described, my improved 75 skate may be of any standard construction. As herein shown, the heel-plate 15 is provided with a struck-up, metal hanger 23 mounting a pair of wheels 24. In like manner, the toe-plate 19 is provided with a hanger 25 80 mounting a pair of wheels 26. The heel-plate is provided with an integral, upturned heel-flange 27 to which fastening straps (not shown) are applied, while the toe-plate is provided with the usual sole-clamps. 85

I claim:

An extension roller-skate having a heel plate and a toe plate, a self-stiffening U-girder extension riveted to each of said plates, and sleeving one within the other, one 90 of said extensions being long enough to have its ends bearing against the under side of each of said plates respectively at all times, and a clamping device for clamping the said extensions together. 95

In testimony whereof, I have signed this specification.

JULIAN S. GRAVELY.
